UNITED STATES PATENT OFFICE.

MARJORIE F. HOSFORD, OF OAK PARK, ILLINOIS, ASSIGNOR TO TOYGRO COMPANY, OF CHICAGO, ILLINOIS, A CORPORATION OF ILLINOIS.

FOLDABLE TOY.

Application filed October 20, 1920. Serial No. 418,192.

To all whom it may concern:

Be it known that I, MARJORIE F. HOSFORD, a citizen of the United States, residing at Oak Park, in the county of Cook and State of Illinois, have invented new and useful Improvements in Foldable Toys, of which the following is a full, clear, concise, and exact description, reference being had to the accompanying drawing, forming a part of this specification.

This invention relates to foldable toys, and more particularly to toys of this character which are capable of being disassembled or knocked down, as well as reassembled with comparative ease and speed and without appreciable depreciation or injury to the elements or parts constituting the toy.

The invention is directed to that general class of toys which are cut out of sheets of foldable material and then folded and fastened into the desired forms. Toys of this character are usually held in shape by fastening suitable edges or portions of the blank or blanks with paste, or by providing locking members which constitute part of the blank, said locking members engaging the blank in the assembled form to hold it in position.

In the toys constructed according to this invention the various blanks or parts are held in place by suitable connectors which are adapted to provide either a rigid or a swivel connection as desired. The connectors are likewise rigidly and easily placed in position, as well as easily removed, so that the toys can be disassembled whenever desired without injuring the blanks from which the toys are constructed.

One of the objects of this invention, therefore, resides in the production of an improved form of toy of this character and the blanks from which such toys are constructed in which the blanks are simple to manufacture, and the toys are readily and easily assembled from the said blank or blanks. The toys when thus assembled are rigid, strong, and durable so as to stand considerable wear and rough usage, the toys at the same time being pleasing to the eye and attractive in appearance.

The toys which may be constructed in accordance with the teachings of this invention may be divided for convenience into

two general groups or classes, namely, the non-roller type, of which tables, chairs, couches, lamps and dressers, etc., are examples, and the wheel or roller type, of which wagons, automobiles, carts, buggies, etc., are examples. The blanks from which both of these two general types of toys are constructed are designed upon a common plan or system whereby the toys when assembled will have a certain desired stiffness, rigidity and solidity, not heretofore acquired in toys of this character. One of the chief objections to foldable toys resides in the fact that such toys are usually of flimsy construction, and this objection applies especially to the protruding portions of the toy, which portions of the toy, when constructed of paper, are very readily distorted or torn.

Another object of this invention, therefore, resides in the production of a system for the design of the blank from which the toys are assembled whereby there will be no flimsy or weak protruding parts, the finished assembled toy in all its sections being constructed to resist ordinary turning, tearing, and twisting forces. This improved construction is obtained by making all those parts of the toy which are likely to be subjected to strains substantially as rigid as the body portion of the toy. The construction is obtained by bending back on themselves such protruding parts of the toy and preferably separating the bent-back portions of the toy by a suitable web, whereby it will be necessary in order to bend, tear or twist the protruding part to do so across the edge of the material from which the toy is constructed. This construction imparts to the toy a rigidity which is commensurate with a toy constructed of solid material. By adapting this system of construction through the entire line of toys, they may be readily made of cardboard or stiff paper and still be as substantially solid and rigid as the ordinary non-collapsible toy constructed of light wood or metal. The toys made in accordance with the teachings of this invention are preferably made of stiff paper or cardboard, but the invention is obviously not limited to toys constructed of this material, as toys of this character can obviously be readily constructed of any other stiff material which

can be readily bent, such as for example, light sheet metal or the like.

A further object of the invention resides in a construction whereby the general appearance of the toys can be changed as desired by utilizing the fasteners adapted to assemble the body of the toy as a securing means for suitable coverings, fanciful or otherwise, for any desired portions of the toy. Thus for example, in the case of furniture such varying forms of upholstery can be secured to the toys as may please the fancy of the child. The decoration of the toys, by means of fanciful covering, gives the toys a more realistic appearance and makes such toys entertaining and instructive.

Other objects of the invention will be apparent from the following description, the accompanying illustrations and the appended claims.

For the purpose of description several embodiments of this invention are illustrated in the accompanying drawings, in which—

Fig. 1 is a view in perspective of a type of chair;

Fig. 2 is a vertical section through the chair illustrated in Fig. 1;

Fig. 3 illustrates the blank of the body member of the chair;

Fig. 4 represents the blank of the seat of the chair;

Fig. 5 illustrates the blank for the front leg members of the chair;

Fig. 6 is an inverted drawing of the blank for the back cover of the chair;

Fig. 7 is an inverted drawing of the blank of the cover for the seat of the chair;

Fig. 8 is a view in perspective of one form of table;

Fig. 9 is a vertical section through one side of the table taken on the plane represented by the line 9—9 of Fig. 8;

Fig. 10 is a longitudinal section of one end of the table taken on the plane represented by the line 10—10 of Fig. 8;

Figs. 11, 12 and 13 represent respectively the blank for the top for the shelf and for the legs of the table;

Fig. 14 is an inverted showing of the blank for the cover of the table;

Fig. 15 is an illustration in perspective of a bed;

Fig. 16 is a longitudinal section through the center of the bed shown in Fig. 15;

Fig. 17 is a section taken on the plane represented by the line 17—17 of Fig. 16;

Fig. 18 is a detailed view showing the manner in which the legs of the bed are folded and fastened;

Figs. 19, 20, 21 and 22 illustrate respectively the blanks for the head, foot-board, side-rails and springs of the bed;

Fig. 23 shows the blank for the spread of the bed;

Figs. 24 and 25 illustrate respectively an inverted view of the covering used for the head and foot-panels of the bed;

Fig. 26 illustrates in perspective a cart and is an example of the roller type of toy;

Fig. 27 is a section taken on the plane represented by the line 27—27 of Fig. 26;

Figs. 28, 29 and 30 illustrate respectively the blanks for the box of the cart, the bolster and the tongue; and

Figs. 31, 32 and 33 show respectively the wheel, the axle and an enlarged end view elevation of the axle.

In the commercial exploitation of this invention the toys of which the accompanying illustrations are typical representations are manufactured in blank form and thus sold to the public. To assemble the toy, the child is consequently called upon: first, to cut out the blanks of a particular toy from a sheet or sheets which contains all the blanks required to construct the said toy: second, crease the blanks on the fold line, and finally, assemble the blank by means of the fasteners through the aligned perforations.

The blanks will be preferably sold to the public in sets, each set incorporating, in the case of furniture, the articles required for one room, as for example, living-room, dining-room, kitchen or bed-room furniture.

In the drawings, Figs. 1 to 7 are typical representations of the blanks and the assembled chair included in a set of bed-room furniture. As will be observed from the figures, there are three blanks shown in Figs. 3, 4 and 5 respectively which are required to construct the body portion of the chair.

Fig. 3 illustrates the blank used for the back and rear legs of the chair. Thus, the part 35 is the front portion of said back, and to it is attached the rear portion of the back 36 and the combined arms and rear legs 37 and 38. In preparing this blank for assembly, the blank is cut on the heavy lines 39, 40, 41 and 42 and creased on all the broken lines such as 43. When the blank has been cut on the heavy lines 39 to 42 inclusive and creased on the broken lines such as 43, it will be observed that by creasing the blank on the broken lines 43 and 44, the protruding back of the chair will be folded back on itself, so that the said back will be composed of two layers with the intervening web 45 at the top of the back.

In a like manner, when the wings 46 and 47 of the blank attached to the portion 36 are folded back on their associated crease lines, the side edges of the chair will be reinforced by the webs 48 and 49 respectively. A similar construction is incorporated in the rear legs whereby the arms of the chair

will be provided with the webs 50 and 51 and 52 and 53 respectively.

The blank shown in Fig. 3 is likewise fitted with the slots 54 and 55, which are utilized to carry the fanciful coverings which it might be desired to attach to the chair to represent upholstery. These slots together with the fasteners inserted through holes 72 and 73 serve as a convenient means for attaching the covering to the chair, but obviously such covering could be carried over the end of the back and the slots omitted, if so desired.

The blank shown in Fig. 3 constitutes the main body member of the chair incorporating the back, the two rear legs of the chair, and the two sides of the chair. The blank from which the front legs of the chair are constructed is illustrated in Fig. 5 and comprises the front portion 56 and the side portions 57 and 58, the side portions being creased on the fold lines 59 and 60. The seat of the chair is illustrated in Fig. 4 and comprises the main seat body 61 and the 4 foldable appendages 62, 63, 64 and 65 which are folded down on the crease lines 66. To assemble the chair, after the blanks have been folded on their respective crease lines, the folded blank illustrated in Fig. 4 is inserted in the folded blank illustrated in Fig. 3, so that the perforations 70, 71, 72, 73, 74 and 75 of the folded blank 3 are aligned with the perforations 76, 77, 78, 79, 80 and 81 of Fig. 4.

The folded blank in Fig. 5 is then placed in position at the front of the chair, as clearly illustrated in Figs. 1 and 2, with the perforations 82, 83, 84, 85, 86 and 87 aligned with the perforations 77, 76, 88, 89, 81 and 80 respectively of the folded blank of Fig. 4, and the perforations 82 and 83 of the blank of Fig. 5 aligned with the perforations 71 and 70 respectively of Fig. 3, and the perforations 86 and 87 aligned respectively with the perforations 75 and 74 of Fig. 3. When the chair has been thus assembled, the various folded blanks can be readily held in shape by inserting through the aligned perforations any type of fastener, preferably the ordinary brass paper fastener, as illustrated at 90 in Fig. 2.

When the folded blanks of Figs. 3, 4, and 5 are thus assembled and held in position by the fasteners inserted through the aligned perforations, the frame-work of the chair is completely assembled in the form shown in Figs. 1 and 2, with the exception that the covering shown in these two figures to illustrate upholstery are not included in the assembly hereinbefore described. It will be noted from the vertical section shown in Fig. 2 that the protruding back of the chair comprises the front and back sections 35 and 36 respectively interconnected by the web 45, and that these two sections are held

in position and attached to the seat of the chair by means of the fasteners 90. This construction gives to this protruding back a solidity and rigidity which is commensurate with the box-body portion of the chair and eliminates from the chair construction a flimsy, easily torn and bent back, such as is ordinarily obtained in foldable furniture when this construction is not utilized. This is particularly true when the furniture is made from folded paper or cardboard.

The same construction is incorporated in the assembled sides 91 and 92 of the chair, the protruding portions of the chair being rigidly and solidly constructed by means of this design, and the box-body portion of the chair being likewise solid and rigid because of the re-enforcing effect of the interconnected blanks. The assembled chair represents an article which very closely simulates an article of furniture made of solid material, not only in strength and rigidity, but likewise in physical appearance. When it is desired to cover the body or frame-work of said chair with a design representing upholstery, cane-work or the like, this can be readily accomplished by cutting blanks adapted to fit over those portions of the chair which it is desired to cover, perforating those blanks at the proper places and then assembling the coverings on the chair over the portions to be covered by the same fasteners 90, which are utilized to assemble the frame-work of the chair as hereinbefore described. For the purpose of illustration, Figs. 6 and 7 show blanks which may be utilized for such coverings. Fig. 6 shows an inverted plan view of the blank of the covering used for the back of a chair, this blank comprising the front portion 94 and the back portion 93, these two portions being connected by the interconnecting web 95, which web is positioned between these two portions between the fold lines 96 and 97. When this covering is to be applied to the chair it is creased on the fold lines, after which one end of the covering is slipped through the aligned slots 54 and 55, at which time the perforations 96' and 97' and the perforations 98 and 99 will be aligned with the perforations 72 and 73, and the perforations 100, 101, 102 and 103, and thus the rear fasteners 90 will serve to hold all of these parts in position, as clearly illustrated in Fig. 2. In a like manner, when it is desired to cover the seat of the chair, a blank such as illustrated in Fig. 7 is used. This blank consists of a main portion 105 and the appendages 106, 107, 108 and 109, which are folded on the crease lines such as 110. This blank covering is inserted over the seat blank illustrated in Fig. 4 before said seat is assembled in the chair, and then when the chair is assembled, as hereinbefore

100

105

110

115

120

125

130

described, the fasteners 90 which hold the chair in its assembled position will hold the seat and its covering in their respective position.

- 5 When the chair is assembled with the coverings, hereinbefore described, in position, it will have a general appearance such as illustrated in Fig. 1. It will be obvious that other coverings may be added to the 10 chair, as for example, a covering may be applied, if desired, to the side arms and also to the legs. These coverings may be of different color and design to suit the fancy of the child. These coverings can 15 readily be cut from wall-paper, colored paper, cloth, and the like. The child is, therefore, in a position, having assembled the frame-work, to lay out and design the 20 general appearance of the chair according to its own artistic desires. Inasmuch as the chair is assembled entirely by the fasteners, such as 90, it can be knocked down and reassembled without any injury to the 25 folded blanks and consequently the coverings of the chair can be changed whenever desired, and the child is, therefore, in a position to change the character and complexion of the furniture whenever it desires. This feature of this furniture incorporates an element which is very entertaining 30 as well as instructive to the child.

In Figs. 8 to 14 is shown a table constructed in accordance with the teachings of this invention. The frame-work of this 35 table is constructed of five blanks, comprising the blank for the top, illustrated in Fig. 11; two blanks for the legs, one of which is illustrated in Fig. 13, and the blank for the shelf, illustrated in Fig. 12. In constructing this table the blanks are cut and folded in a manner identical with that described for the chair illustrated in Figs. 1 to 7. Thus the top of the table 111 carries 40 the four appendages 112, 113, 114 and 115, all of which are folded on the crease lines indicated and whereby the protruding top portion of the table 116, as illustrated in Fig. 9, will be folded back on itself to give 45 this portion of the table the desired stiffness and rigidity. This protruding portion 116 in this table extends but a short distance beyond the side face of the table, and consequently the construction shown in Fig. 9, in which no substantial intervening web 50 is utilized at the extreme end, gives sufficient strength and rigidity. The two leg members, one of which is illustrated in Fig. 13, are folded on the crease lines 118 and 119, and when thus folded the perforations 120, 121, 122 and 123 of one set of legs will be 55 aligned with the perforations 124, 125, 126 and 127 respectively of the table-top, the perforations of the table-top 128 and 129 aligning respectively with the perforations 60 125 and 126. The shelf 130 is cut on the

solid black lines 131, 132, 133, and 134 and creased on the broken lines, and is then inserted in position, as indicated in Figs. 8 and 9, at which time the perforations such as 135 and 136 at each corner will be aligned 70 with the lower perforation 137 at each leg. When the three table blanks have been thus folded and assembled, it will be obvious that they can be readily held in their respective position to construct the assembled 75 table shown in Fig. 8 by fasteners such as 90.

When it is desired to cover any portion of the table, this is accomplished in substantially the same way as was described 80 in connection with the chair illustrated in Figs. 1-7. In the specific embodiment shown, a table-cloth 138 is illustrated, the blank of which is shown in Fig. 14. This blank consists of a top portion 139 and 85 the two appendages 140 and 141 separated from the top by suitable folded lines. When this table-cloth has been folded on these lines it is inserted in position over the table-top 111 and its appendages 140 and 141, 90 will readily hold it in this position without fasteners due to the form of creasing. Obviously, if desired, a cover for the entire top could be placed on the table, and various coverings could be utilized for the legs, 95 and these coverings fastened to the frame-work by the fasteners used to hold the frame-work of the table together. The coverings used for the table-top cover and the coverings used for the legs and shelf could 100 be designed to simulate anything desired. The coverings for the legs, for example, could be such as to simulate various types of wood; whereas, the cover for the table-top could simulate either a fancy cloth cover, 105 oil-cloth, etc.

Figs. 15-23 illustrate a form of bed and the blanks from which it is constructed, which bed and blanks incorporate the improved construction following the teachings 110 of this invention. The frame-work of the bed is constructed from four blanks comprising the head-board blank, illustrated in Fig. 19; the foot-board blank, illustrated in Fig. 20, and two side-rails, one of which 115 is illustrated in Fig. 21. The head-board of the bed 142 is constructed of the blank illustrated in Fig. 19, which comprises the main portion 143 and the appendages 144, 145, 146, 147 and 148. This blank is cut 120 on the solid lines 149 and 150. After thus cut, the blank is folded on the crease lines shown, the appendages 144 and 146 being folded inwardly so that the perforations 151, 152, 153 and 154 will align with the 125 perforations 155, 156, 157 and 158 respectively. When these perforations are aligned and the blank properly folded on the crease lines, the protruding upper portion of the head-board will be folded back on itself 130

to give it solidity and rigidity, said folded back portion being interconnected to the main portions of the bed 143 by means of the webs 160 and 161. The upper appendage is folded inwardly in the same manner so that the perforations of this appendage, 162 and 163, will align with the perforations 157 and 155 respectively. The appendages 147 and 148 are then turned in and bent on the crease lines, the leg portions 164 and 165 being folded in triangular shape as illustrated in Fig. 18, and held in place in the folded form by a fastener 90.

The foot-board illustrated in Fig. 20 consists of the main portion 166 and the appendages 167, 168, 169, 170 and 171. The blank is cut and creased on the lines hereinbefore described, and when it has been folded the perforations 172 and 173 will align with the perforations 174 and 175, and the perforations 176 and 177 will align with the perforations 174 and 175. The leg portions 178 and 179 on the foot-board are folded and assembled the same as were the leg portions of the head-board.

The side-rails, as illustrated in Fig. 21, consists of two sections, 180 and 181 respectively, interconnected by the web 182. These side-rails are creased on the fold lines shown, so that this blank is bent back on itself whereby the perforations 183 and 184 will be aligned with the perforations 185 and 186 respectively.

When the head-board and foot-board have been thus creased and assembled, they are ready to receive the side-rails so as to complete the frame-work of the bed. The side-rails of the bed are slipped over the upper portion of the appendages 147, 148, 169 and 170, so that the perforations 183 and 185 at one end of the side-rail will be aligned with either one of the perforations 188 in the head-board and the perforations 184 and 186 will align with either one of the perforations 189 in the foot-board. When the blanks constituting the frame-work have been thus assembled, the frame-work of the bed will have a general appearance, as illustrated in perspective in Fig. 15.

When the frame-work of the bed is thus assembled, the leg portion in the triangular shape illustrated in Fig. 18 will protrude inwardly and will serve as a suitable support for the spring, which can thus be removably positioned in the frame-work of the bed, if so desired. In the preferred embodiment shown in the illustrations, the spring blank is arranged to be secured in its position in the bed frame-work by the same fasteners 90 which secure the side rails of the bed to the head and foot-boards.

The blank for the spring is illustrated in Fig. 22 and comprises the center position 190 and the appendages 191, 192, 193 and 194. The blank 190 is cut on the solid black

lines 195, 196, 197 and 198 and creased on the broken fold lines, the same as for other blanks hereinbefore described. When the blank for the spring has been cut and folded on the crease line, the perforation 199 will be aligned with perforation 200, perforation 200' will align with perforation 201; perforation 202 will align with perforation 203, and perforation 204 will align with perforation 205. If the spring is to be loosely assembled in the bed frame-work, fasteners will be passed through these aligned perforations to hold the spring in its folded position when the spring can be placed in the frame work, without fastening it thereto. However, in the preferred embodiment the fasteners which secure the side-rails to the head and foot-boards are passed through the aligned perforations of the bed spring to hold the bed spring in position in the frame-work. This is clearly illustrated in Fig. 17. In a like manner the perforations 208, 209, 210 and 211 of the bed spring, when assembled in the bed frame-work, will align with the perforations 156 and 158 and 174 and 175 at the lower part of the head and foot-boards respectively, and the fasteners will be inserted through the spring, as well as these perforations and the perforations in the folded back appendages 144 and 146 of the head-board and 168 and 177 of the foot-board. The manner in which these fasteners pass through the head and foot-board and the ends of the spring is clearly illustrated in Fig. 16.

Obviously, if desired, the spring and bed frame-work may be suitably covered to simulate any material desired, so as to give the bed a more realistic appearance. For this purpose the spring may be covered with a spread, as illustrated in Fig. 23, which spring comprises the center 212 and the appendages 213, 214 and 215. The spread is cut and folded on the same lines as hereinbefore described and is placed over the spring and held in position by the same fasteners which hold the spring in position, as clearly illustrated in Figs. 15, 16 and 17.

For the purpose of illustrating the manner in which the frame-work of the bed may be covered, a head-board panel blank is shown in Fig. 24, which blank consists of the center portion 216 and the foldable appendages 217, 218, 219 and 220. This blank is folded on the crease lines indicated and is secured to the head-board by the fasteners used in the original assembly, as clearly illustrated in Figs. 15 and 16. In Fig. 25 is shown a panel which may be used for the foot-board, which panel consists of the center portion 221 and the foldable appendages 222, 223, 224 and 225. This foot-board panel blank, when creased on the fold lines, is inserted in position, as clearly illustrated in Figs. 15 and 16.

16, and held in position by the fasteners used in the original assembly. The panels illustrated in Figs. 24 and 25 may be marked to imitate any desired material and for the

5 purpose of illustration in the preferred embodiment shown in the drawings, these panels have been marked to illustrate cane or wicker-work.

10 When the bed has been completely assembled with the various coverings attached thereto, as illustrated in Fig. 15, it comprises a solid, rigid structure which cannot be easily torn, bent, twisted or distorted and one which may be readily assembled and knocked down at will. Likewise, because of the facility with which the bed can be assembled and the corresponding ease with which coverings of various designs may be applied to the frame and spring structure, 15 it will be evident that the general complexion and appearance of the bed can be readily changed to suit the fancy of the child without in any way injuriously affecting the folded blanks from which the bed is constructed because of the tearing apart and assembling of the structure.

Figs. 26 to 33 illustrate a form of roller type toy constructed in accordance with the teachings of this invention. The toy there 20 shown comprises an ordinary cart or wagon, but obviously the principles incorporated in its construction are readily applicable to any other form of roller toy which it may be desired to build. The illustrative form of 25 roller toy shown in these figures comprises four main foldable blanks.

Fig. 28 illustrates the blank for the box of the cart and this blank 230 comprises a main portion 231 and the appended foldable portions 232, 233, 234, and 235. Each of these 30 appended foldable portions consists of two parts interconnected by a web, one of which is folded back on the other and which is connected to the other by means of an intervening web such as 236. This blank is cut and folded in the same manner as hereinbefore described for the previous toys and the blanks interconnected by fasteners such as 90, which pass through the aligned perforations when the blank is folded, as hereinbefore described. It will be noted that the 35 box of the wagon, when thus assembled, has all of its upwardly protruding parts, that is the sides, constructed of material which is bent back upon itself and which is interconnected by intervening webs such as 236. This, as hereinbefore explained, gives to the upwardly protruding side portions of the wagon-box the necessary stiffness, solidity and rigidity, as well as simulating the 40 appearance of being constructed of solid material.

Secured to the rear portion of the box of the cart or wagon is a bolster such as illustrated in Fig. 29. This bolster consists of

the two side portions such as 240 and 241 interconnected by the part 242. The blank is folded on the broken lines, as indicated in the figure, and when thus folded the perforations 243, 244, 245 and 246 will all be in alignment under substantially the center portion of the interconnecting part 242. When thus aligned, these parts are all interconnected by a fastener 90, as illustrated in Fig. 27. The rear bolster is connected to 75 the box of the wagon or cart by means of perforations 247 and 248 in the bolster which will align with perforations 249 and 250 in the main portion 231 of the box blank.

When these perforations are thus aligned, 80 the bolster is connected to the box by means of fasteners such as 90, as illustrated in Fig. 26. The bolster for the front part of the wagon is assembled in the same manner but is connected to the front end of the box by 85 means of a single fastener which passes through the perforation 251 in the bolster and 252 in the box, whereby a swivel connection is obtained between the front bolster and the wagon-box. The perforations 252 90 and 253 in the bolster are adapted to receive the axle 254 illustrated in Fig. 32, which axle is preferably composed of some light form of wood or metal wire. Secured to each end of the axle is a wheel such as 255 95 illustrated in Fig. 31, which wheel is preferably made of heavy cardboard or fibre or some other form of stiff, light material. The wheel is retained in position on the axle by slitting the ends of the axle crosswise as indicated at 256 and 257 in Fig. 33. Thus, after the wheel is slipped over the end of the axle, these crosscuts on the end of 100 said axle may be pried out slightly to hold the wheel in position.

Secured to the front bolster by means of the fastener 90, which passes through the aligned perforations 243-246 inclusive, which retains said bolster in shape, is the tongue of the wagon, the blank for which is 105 illustrated in Fig. 30. The blank from which the tongue 258 of the wagon is constructed comprises the center portion 259 and the three appended foldable portions 260, 261 and 262. The blank for the tongue 110 is folded on the crease lines, and when thus folded the two downwardly extending portions 261 and 262 are held in position by means of a rod 263 which passes through the aligned perforations 264 and 265. These 115 downwardly turned portions 261 and 262, together with the rod 263, tend to give the tongue the required stiffness or rigidity. The tongue is connected to the front bolster by means of the perforation 266 through 120 which passes the fastener 90 which retains the front bolster in its folded position. When all of the blanks of the wagon have been folded, as hereinbefore described, and 125 assembled by means of the fasteners, the 130

cart has a general appearance, as illustrated in perspective in Fig. 26. The cart, as there shown, can be readily drawn about by the tongue of the wagon when the wheels will readily rotate with the axle, the axle rotating in the perforations 252' and 253' of the front and rear bolsters. A cart when constructed as hereinbefore described, and illustrated in perspective in Fig. 26, has sufficient strength and possesses the required solidity and rigidity to carry considerable weight. A cart thus constructed is commensurate in strength with the average cheap toy made of wood-veneer or of very light sheet metal.

Obviously, the construction of the cart, as is the case of the toys hereinbefore described, is readily adapted to receive coverings to represent materials of varying character. Thus the body, bolsters and tongue 20 may be covered, if desired, with a suitable material to represent the various types of material ordinarily used in constructing this type of article.

Obviously, a large number of various characters of roller toys can be constructed in which the general teachings of this invention and the principles involved could be employed, but for the purposes of illustration, the single type of roller toy, illustrated in Figs. 26-33 is sufficient to indicate the general scheme and system to be employed.

It will now be evident from the foregoing description that the toys constructed according to this invention have a number of very distinct and advantageous features. Thus for example, the toys can be very readily assembled and knocked down without any perceptible injury to the blanks used to construct the toy. This is possible because of the manner in which the toys are interconnected, as the fasteners can be readily inserted through the aligned holes and removed without in any way injuring the blanks. Likewise, the system of folding is so designed that the protruding parts or exposed edges of the toy, which ordinarily would be of very weak and flimsy construction, are re-enforced in such a manner that these protruding parts are just as solid, strong and rigid as the body portion of the toy. Further, because of the improved method of interconnecting the various blanks, the different sections or parts of the toy can be readily covered so as to give to such parts an appearance which closely simulates the appearance of these parts in the actual structures of which the toys are miniature reproductions. If desired, it is obviously apparent that the various blanks from which the toys are constructed can be made of material having different colors so that the toy, when assembled without any coverings, will have a certain definite physical appearance and gen-

eral complexion, and due to the construction, this complexion of the toy can be readily changed by applying suitable coverings.

Obviously, the invention is not limited to the specific embodiments thereof herein illustrated and described, but the invention is capable of many variations and other applications, the spirit and scope of the invention being set out in the following claims.

Having thus described my invention, what I claim as new and desire to secure by Letters Patent, is:

1. A new article of manufacture comprising a knock-down toy made from foldable material consisting of blanks fitted with perforations and fold lines, protruding portions in said toys when assembled, said protruding portions comprising material bent back on itself, an intervening air chamber separating said bent back portions whereby they acquire the desired stiffness and rigidity, a web of substantial width bent at substantially right angles interposed between said bent back portions, paper fasteners, said web and said paper fasteners maintaining the bent back portions of said toy in fixed relationship, and said paper fasteners passing through aligned perforations in the folded material when assembled, the said perforations and fasteners serving to properly position the various parts of said toy and being the sole means for holding it in its assembled relationship.

2. A new article of manufacture comprising a knock-down toy made from foldable material consisting of blanks fitted with perforations and fold lines, paper fasteners, said blanks being folded and interconnected by said fasteners passing through said perforations when the toy is assembled in its fold relationship, said blanks constituting the frame-work of the toy, a covering for said toy fitted with perforations and fold lines, which covering when folded will fit over said frame-work and its perforations aligned with the perforations in the frame-work, said coverings being held in position by the same fasteners used to assemble the frame-work, the perforations together with the fasteners serving to properly position the various parts of said toy and being the sole means for holding it in its assembled relationship.

3. A new article of manufacture comprising a knock-down toy made from foldable material, said toy being composed of interconnected blanks which constitute the frame-work of the toy, perforations in said blanks and fasteners provided to pass through the perforations in said blanks when assembled in its folded relationship to maintain the toy in its assembled condition, coverings adapted to be removably applied to said frame-work, perforations and fold lines in said coverings, the covers, when

- creased on said fold lines, being adapted to be applied to said frame-work, the perforations in the coverings being aligned with the perforations in the frame-work and the fasteners utilized to assemble the frame-work serving to secure the coverings to the frame-work of said toy.
4. A new article of manufacture comprising a knock-down toy made from foldable blanks, perforations in said blanks, standard interconnecting fasteners used to interconnect said fold blanks to construct an assembled toy, coverings adapted to be placed upon said assembled toy, perforations and fold lines on said covers, the perforations in said coverings, when folded and applied to the assembled toy, aligning with the perforations in the toy blank, the fasteners utilized to assemble the toy being used to interconnect the coverings on the assembled toy, the blanks constituting the frame-work of the toy and the covers for said blanks being interchangeable for the purpose of varying the general appearance of the toy.
5. A new article of manufacture comprising a knock-down toy made from foldable blanks, perforations in said blanks, said

blanks being designed so that the protruding portions thereof in the assembled toy will be folded back on themselves with an intervening web, and so that said portions will be substantially as rigid and solid as the body of the toy, standardized connectors for assembling said toy and retaining the folded portions of the protruding parts in the assembled position, said connectors passing through aligned perforations in the folded material, said perforations and connectors serving to properly position the various parts of said toy and being the sole means for holding it in its assembled relationship, coverings adapted to be applied to the desired portions of said toy to give it a more realistic appearance, fold lines and perforations in said coverings, the perforations in said coverings when applied to the assembled toy aligning with perforations in the toy blank, said coverings being retained in position by the same connectors utilized to assemble the blanks constituting the toy.

In witness whereof, I have hereunto subscribed my name.

MARJORIE F. HOSFORD.
